UNITED STATES PATENT OFFICE.

WESLEY S. JUDY, OF DAYTON, OHIO.

STITCHING-CLAMP.

1,031,271.

Specification of Letters Patent.

Patented July 2, 1912.

Application filed February 12, 1912. Serial No. 677,034.

To all whom it may concern:

Be it known that I, WESLEY S. JUDY, a citizen of the United States, residing at Dayton, in the county of Montgomery and 5 State of Ohio, have invented certain new and useful Improvements in Stitching-Clamps; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 This invention relates to certain new and useful improvements in stitching clamps for holding articles to be stitched by hand, in a convenient position for the work.

The object of the invention is to provide 20 a convenient and effective clamp to be placed on the leg above the knee, in such position, that the jaws of the clamp may be tightened or relaxed in proportion to the extension of the lower portion of the leg, as will herein- 25 after more fully appear in the following description in connection with the accompanying drawings, of which—

Figure 1 is a side elevation of the clamp showing the same closed. Fig. 2 is a top 30 plan view of the clamp as shown in Fig. 1. Fig. 3 is a side view showing the clamp in position for service.

In a detail description of the device, the same reference characters indicate the same 35 parts in the drawings and description.

1 designates a curved plate, the curvature of which conforms to the leg above the knee. This curved plate has an extension 2 extending from the upper side thereof at a central 40 point, with an aperture therein to receive a pin 3. On opposite sides of this extended portion 2 are fulcrumed levers, the ends 4 and 5 of which extend approximately to the ends of the curved base plate 1, and are pro- 45 vided with apertures 6. The upper portions 7 and 8 of said levers are curved to provide ample space between them and the jaws 9 are lengthened to provide a substantial clamping surface for the article, which is 50 held therebetween.

It will be understood that the device is especially useful for mending harness or other articles to be mended by hand, the article being stitched being held securely between the jaws 9, and the space beneath said jaws 55 being ample to accommodate the article being worked upon. Secured to the ends 4 and 5 of the levers is a strap 10, which is adjusted by means of a buckle 11, the ends of said strap being attached to the eyes 6 in 60 any suitable manner.

In operation the curved plate 1 is placed upon the knee as shown in Fig. 3, and the strap 10 is placed below the foot, and is securely held in position by extending the 65 lower portion of the leg. To release the jaws of the clamp for the insertion of the article to be stitched, the lower portion of the leg is moved backwardly to release the tension of the strap 10.

Having described my invention, and the manner of its use, I desire to claim:

1. A stitching clamp comprising a curved base plate adapted to fit and rest upon the knee of an operator and having a fulcrum 75 lug extending from the upper side thereof, clamping levers pivoted to said lug, the lower portions of said levers being extended approximately to the ends of the curved base plate and the upper portions of said 80 levers being curved and terminated in clamping surfaces extended laterally on each side of the levers, and a flexible member united to the ends of the levers and adapted to extend below the foot whereby the clamp- 85 ing levers are manipulated to hold or release the article to be stitched.

2. A stitching clamp comprising a base plate adapted to fit and rest upon the knee of an operator, clamping members supported 90 on said base plate, and a strap attached to the said clamping members and adapted to extend under the foot, substantially as specified.

In testimony whereof I affix my signature, 85 in presence of two witnesses.

WESLEY S. JUDY.

Witnesses:

R. J. McCARTY,
MATTHEW SIEBLER.
